MODULAR DISPLAY CASE FOR FABRICS OR THE LIKE

Ann M. Turdo, New York, N.Y., assignor to Mod
Displays, Inc., New York, N.Y.

Filed Jan. 8, 1973, Ser. No. 321,569

Term of patent 14 years

Int. Cl. D20—02; D6—04
U.S. Cl. D6—186

FIG-2

4

4

FIG. 1 is a front perspective view of a modular display case for fabrics or the like, embodying my new design;
 FIG. 2 is a top plan view thereof;

FIG. 3 is a front elevation view thereof the rear view being the mirror image of FIG. 3; and

FIG. 4 is a vertical transverse section view, taken along the line 4—4 of FIG. 3.

The bottom of the display rack is plain.

I claim:

The ornamental design for a modular display case for fabrics or the like, as shown and described.
